(57) **CLAIM**

The ornamental design for a display screen or portion
thereof with graphical user interface, as shown and
described.

DESCRIPTION

The file of this patent contains at least one drawing/photograph
executed in color. Copies of this patent with color
drawing(s)/photograph(s) will be provided by the Office
upon request and payment of the necessary fee.

The sole FIGURE is a front view of a display screen or
portion thereof with graphical user interface showing the
claimed design.

The peripheral dashed broken lines illustrate a display
screen or portion thereof and form no part of the claimed
design.
